UNITED STATES PATENT OFFICE.

ELMER A. WATTS, OF SPRINGFIELD, OHIO.

PUMP.

1,202,932.

Specification of Letters Patent. Patented Oct. 31, 1916.

Application filed December 2, 1915. Serial No. 64,779.

To all whom it may concern:

Be it known that I, ELMER A. WATTS, a citizen of the United States, residing at Springfield, in the county of Clark and State 5 of Ohio, have invented certain new and useful Improvements in Pumps, of which the following is a specification, reference being had therein to the accompanying drawing.

This invention relates to pumps for raising 10 fluids from a great depth through successive stages.

The invention embodied in this application is in the nature of a further development of the invention embodied in the application filed by Irwin L. Dunn and myself April 19, 1915, Ser. No. 22,296. This invention, like the one embodied in said application, is adapted for use in very deep wells. In the pump shown in the former application it is necessary to allow the lower 20 chambers to remain idle while the upper ones are operated.

It is an object of this invention to obviate this feature and to devise means to allow 25 one chamber to fill while the other is emptying, thereby enabling the handling of greater quantities of fluid.

It is a further object of the invention to provide a displacement pump which will lift 30 a quantity of fluid to a great height with a relatively low air pressure.

It is a further object of the invention to devise means to keep the various valves in an operative and unclogged condition.

35 It is a further object of the invention to provide independent mechanism in each chamber to control the admission and exhaustion of air.

It is also an object of the invention to provide 40 an air intake pipe and an air exhaust pipe common to the several mechanisms.

Another object of the invention is to provide 45 certain improvements in valve construction shown, described and claimed in Letters Patent No. 1,187,579, granted to Irwin L. Dunn and myself June 20th, 1916.

One embodiment of my invention is shown in the accompanying drawings, in which—

Figure 1 is an elevation of the displacement pump located in the well, parts being broken away for clearness and compactness; Fig. 2 is an enlarged cross section on the line 50 2—2 of Fig. 1, looking in the direction of the arrows; Fig. 3 is a vertical longitudinal

section on the line 3—3 of Fig. 2, parts being 55 broken away and looking in the direction of the arrows; Fig. 4 is a vertical transverse section on the line 4—4 of Fig. 2, looking in the direction of the arrows and showing the valve mechanism of the upper chamber with 60 the exhaust valve open; Fig. 5 is a vertical, transverse sectional view of the lower chamber showing the valve mechanism thereof, the intake valve being open; Fig. 6 is a longitudinal, vertical sectional view on the line 65 6—6 of Fig. 2, looking in the direction of the arrows; Fig. 7 is a cross section on the line 7—7 of Fig. 4, looking in the direction of the arrows; Fig. 8 is a cross section on the line 8—8 of Fig. 4, looking in the direction of 70 the arrows; and Fig. 9 is a cross section on the line 9—9 of Fig. 4, looking in the direction of the arrows.

In the embodiment of the invention shown in the above views, Fig. 1 shows the 75 general arrangement in which, as indicated at 1, is shown the outer casing. At 2 is indicated a pocket with which the mechanism communicates. Within the pocket 2 and extending below the casing 1 is the lower 80 chamber having the usual casing 3. This chamber communicates with a source of fluid supply through the valve-controlled opening 4. Extending upwardly from the bottom of the said casing 3 within the chamber is an 85 oil discharge pipe 5 communicating with an upper chamber, as will be described later. Communicating with a source of compressed air and with the lower chamber is an air intake pipe 6. Also communicating with this 90 lower chamber is an exhaust pipe 7. These two pipes 6 and 7 terminate within a casting 8 containing valve mechanism for controlling the lower chamber. This casting 8 is attached to the casing 3 through the instrumentality of a sleeve 8', as clearly shown in Fig. 5. Automatic means for controlling the said valve mechanism within the casting 8 is shown at 9. The device here shown comprises a pair of weights mounted in tandem. It will be understood that as the fluid rises around these weights within the casing 3 they will be relatively displaced owing to the buoyancy of the said fluid.

Connecting these weights and extending 105 above them is a rod 10 slidably passing through a fixed abutment 11 which is mounted on the end of a hanger 12 at

tached to the casting 8 in any suitable manner. The upper end of this rod 10 is screw-threaded, as clearly shown in Fig. 5, and has an adjustable knurled thumb piece 13 which 5 acts as an abutment for the spring 14 which is located between the same and the abutment 11. It will be seen that the spring 14 can be adjusted to vary the tension thereof. When the pump is normally working, the 10 force upward, due to the tension of the spring, is less than the effects of gravity upon the weights 9. However, as the casting 3 fills, the tension of the spring will raise the weights, causing the latter to operate the 15 valve mechanism with which they are connected, as will be more fully described. Above the lower casing 3 is a casing 15 having a chamber into which the fluid from the lower casing is discharged through the oil 20 discharge pipe 5. Mounted in a manner similar to the structure shown in the lower casing the upper casing also has a casting 16 for valve mechanism at its upper end and this casting is attached within the said casing 15 through the instrumentality of a sleeve 16', as shown in Fig. 4. A pair of weights 17 are likewise located in this upper chamber. A rod 18, similar to the rod 10 mentioned above, is slidably mounted in an 25 abutment 19 at the end of a hanger 20. At 21 is a knurled thumb piece screw-threaded upon the rod 18. Between the thumb piece 21 and the abutment 19 is a spring 22 which operates in the manner described above. An 30 oil discharge pipe 23 is shown, extending from near the bottom of the casing 15 out through the top thereof, communicating with the place of storage for the same. It will be understood that the air intake 6 and 35 the air exhaust pipe 7 are in suitable communication with the valve mechanism of the casting 16, as is clearly shown in Fig. 4 and will be more fully described hereafter. At the upper portion of the air intake pipe 40 and air exhaust pipe 7 is a connecting pipe between the two, indicated generally at 24. A suitable three way valve 25 makes it possible to admit compressed air to the 45 exhaust pipe. This arrangement insures the blowing out and cleaning of the various valves of the pump, the operation of which will be described later. A gas discharge pipe 26 allows the gas which accumulates within the pump to escape. The entire 50 structure shown in Fig. 1 is supported by a suitable head 27. It will be understood, although I have only shown in this particular embodiment of the invention two chambers in superimposed relation, that any number 55 of chambers can be used according to the depth of the well and the amount of compressed air available. Two chambers only have been shown for the sake of compactness and to avoid unnecessary drawings.

60 By reference to Fig. 4 it will be seen that

the air intake pipe 6 has a portion screw-threaded, as shown at 28, into the casting 16. A passage 29 below the same communicates with a chamber 30 and this chamber has screw-threaded into it, as indicated at 31, 70 the other portion of the air intake pipe 6. It will be noticed that compressed air has a free channel through the casting 16 to the lower chamber. Communicating with the passage 29 is a vertical opening or bore 32 75 within which is placed a valve piston 33. At its upper end this valve piston has a valve face 34 which co-operates with a valve seat, as indicated at 35, formed in the casting at the top of the bore 32. This latter 80 arrangement constitutes an intake valve and, as shown in Fig. 4, the same is seated. Below this valve structure is a reduced portion 34' of the valve piston located within the chamber 36, said chamber being an 85 enlargement of the bore 32. This chamber 36 communicates with the interior of the casting 15 by means of ports 37, as shown in Fig. 3. At the medial portion of the valve piston 33 is a reduced portion 38 within a 90 chamber 39, this chamber 39 being a part of the bore 32. Below this reduced portion the valve piston 33 is beveled to constitute a valve face 40. This portion 40 co-operates with a valve seat 41 formed within the bore 95 32. Below the valve seat 41 are located ports 42 communicating with the chamber within the casing 16, as shown in Fig. 9. Above the ports 42 and above the valve face 41 is located a port 43. In the position 100 shown in Fig. 4 the last-described valve structure constitutes an exhaust valve, and, as shown, the same is open. It will be apparent that the compressed air within the chamber of the casing 16 may escape 105 through the port 42 and out through the port 43. This port 43 communicates with a chamber 44 having an opening or port 45. This port 45 communicates with a chamber 46 within which is a ball valve 47. The 110 port or opening 45 constitutes the valve seat for the same. At the upper portion of the chamber 46 is a screw-threaded opening 48. Within this opening 48 is a bushing 49 extending into the chamber to form a cage to 115 prevent the ball valve 47 from unseating unduly. This bushing is also apertured to allow free passage of the exhaust. Within the bushing is screw-threaded the upper portion of the exhaust pipe 7, as indicated 120 at 50. Communicating with the chamber 46 is a passage 51 screw-threaded at 52^a, with which the portion of the exhaust pipe leading from the lower chamber is connected.

125 It will be seen from the above description that the exhaust from the lower chamber has an uninterrupted passage to the air past the upper chamber, while the upper chamber is connected with the said exhaust by means of a branch conduit, suitably protected by 130

means of the check valve 47. It will be apparent that the fact that the lower chamber is in a condition of exhaust does not prevent the opposite condition in the upper 5 chamber.

The means for operating the valve mechanism shown in Fig. 4 will now be described. Communicating with the passage 29 is a vertical bore 52 extending through the casting. The lower portion of the bore 52 has a valve face 53 upon which is seated a valve 54. This valve 54 has a stem 55 with a suitable head thereon and above the same is located a spring 56 within the bore and this 10 spring normally tends to hold the valve 54 upon its seat 53. In the lower portion of the bore 52 and below the valve 54 is located a transverse passage 57 within the casting. This passage has a portion at right angles 15 thereto, indicated generally at 58, which opens into the lower portion of the bore 32 in which the valve piston is located. This last-mentioned opening is indicated at 59. Communicating with the passage 58 is a 20 passage 60. This passage is controlled by means of a valve 61 located therein. This valve is normally held in seated position by means of a spring 62 located in the passage 58. The passage 60 terminates at its opposite 25 end in a valve seat 63, upon which is mounted a ball valve 64 constituting a check valve. This check valve 64 is normally held in place by means of a spring 64'. Communicating with this passage 60 is 30 a bore 65. This bore 65 also communicates at its opposite end with the chamber 44. A vertical bore 66 extends from the bottom of the casting and communicates with the bore 52 below the valve 54. Within this bore is 35 slidably mounted a pin 67. The valve 61 also has below it a vertical bore 68 extending through the bottom of the casting. A stem 69 of the valve 61 is slidably mounted within the bore 68. Mounted below the casting 40 16 on a suitable hanger 70 is a lever pivoted at 71. This lever has arms 72, 73 and 74. The arm 73 engages the pin 67 and the arm 74 engages the stem 69. The arm 72 is operated by means of a lever 75 pivoted at 76 45 16 and having a fork 77. The fork 77 engages the lower portion of the arm 72. The lever 75 is suitably and in an operative manner connected with the rod 18 carrying the weights 17. This connection is indicated at 50 55 77'. Above the operative connection 77' is situated a stop 78 which prevents undue movement of the weight 17. In connection with the valves 53 and 61 it should be noted that the action of these valves will be successive. When the lever 72 is moved to the left the valve 61 will be lowered and seated before the pin 67 has moved upwardly sufficiently to unseat the valve 54. The portion 50 55 60 of the oil discharge pipe 23 located 65 within the casing 15 is screw-threaded at its

upper end, as shown at 79, Fig. 3, into the casting 16. The casting 16 has above the said screw-threaded portion a chamber 80. The upper portion of the oil discharge pipe 23 has located therein a check valve. This 70 feature also is shown in Fig. 3. It will be noticed that the opening 81 above the chamber 80 is screw-threaded and a cage 82 is suitably mounted and screw-threaded within this opening 81. The upper portion of the 75 pipe 23 fits over this cage, as clearly shown in said figure. Within the cage is a suitable ball 83 constituting the check valve. It may be stated that a similar check valve is located in the discharge pipe above each chamber, no 80 matter how many are used, and a check valve is also located in the oil discharge pipe above the lowermost chamber.

In Fig. 5 is shown the valve mechanism for the lowermost chamber. The mechanism 85 of this chamber is substantially the same as the mechanism in the upper chambers, but as this is the lowest chamber the air intake pipe 6 will terminate therein and the air exhaust pipe also will terminate in said chamber. As shown in Fig. 5 the air exhaust pipe is screw-threaded into the upper portion of the casting 8, as shown at 84. This exhaust pipe communicates with a passage 85. It will be noted that no check valve is 90 located in the portion 85 communicating with the pipe 7, as it is not necessary. It will also be noted that the passage 87 similar to the passage 29 described in connection with the upper chamber does not communicate with 100 any chamber 30 or its equivalent. Screw-threaded in an opening 86 above the passage 87 is the end of the air intake pipe 6. At 88 is indicated a check valve in the oil discharge pipe leading from the casting 8. It will be 105 understood that the structure of this check valve is identical with the structure illustrated in Fig. 3. The structure of the other portions of the valve mechanism is substantially as above described in connection with 110 Fig. 4. At 32' is shown the longitudinal bore in which the valve piston 33' is located. A port 37' corresponds with the port 37 described above. At 42' is indicated the exhaust port and at 43' is indicated the passage 115 communicating with the exhaust pipe 7. The other portions of the mechanism, indicated generally at 54', 57', 59', 60', 61', etc., are substantially identical with the parts described in connection with the upper cylinder 120 or chamber and shown in Fig. 4.

In the operation of the pump it will be assumed that the lower cylinder 3 is filled. Such being the case, the weights 9 will assume their raised position and will thereby 125 rotate the lever 75'. This lever 75' being in engagement with the lever 72' will rotate the same. The lever 72' being rotated will move one of its arms out of engagement with the stem 69' of the valve 61', allowing the 130

same to close. Continued movement of this lever 72' will raise the pin 67' and move the valve 54' out of its seat. As the valve 54' is moved out of its seat the compressed air will pass down through the passage 52' from the air intake 6 and through the passage 87 past the valve 54', through the passage 57' and out through the port 59' into the bottom of the bore 32'. It will then be noticed that 10 the valve piston 33' will be shifted to seat the exhaust valve and to unseat the intake valve. The valve piston 33' at its bottom has a larger area than the upper portion thereof and the pressure being unequal on the two 15 sides the same will be easily shifted. It will be clear that when the valve piston 33' has shifted to the position shown in Fig. 5 the compressed air passing down through the air intake pipe 6 will pass around the intake 20 valve and out through the passage 37' into the lower cylinder. The fluid therein will then be forced into the next succeeding chamber. As shown in Fig. 4 this chamber will be in a condition of exhaust, that is, 25 there is nothing to prevent the fluid from entering the upper chamber. When the upper chamber has about filled and the lower chamber has about emptied the weights in the lower chamber will again lower, owing to 30 the decrease in buoyancy of the fluid thereon and the reverse operation will take place, namely, the valve 61' will be raised and the valve 54' will be lowered. It will be noticed 35 that the compressed air will thereby be shut off from the bottom of the valve piston 33' and as the valve 61' controls the passage 60' which communicates through the passage 65' with the exhaust pipe, the valve piston 33' will be shifted to open its exhaust and to 40 close its intake valve, assuming a position similar to that shown in Fig. 4. As the fluid leaves the lower chamber and enters the higher chamber it will be clear that the weights 17 thereof will finally rise under the 45 tension of the spring 22, the buoyancy of the gradually rising fluid within the upper chamber allowing this. When the upper chamber is filled the same operations described in connection with the lower chamber 50 take place, namely, the valve 53 will be unseated and the valve 61 will be seated. This will open the air intake valve 34 and allow the compressed air passing down the air intake pipe 6 to pass out at 37 into the upper 55 chamber, forcing the fluid out. The check valves above the respective chambers and within the oil discharge pipes prevent the return of the oil when the chambers are filling. It will also be seen that there is nothing 60 to prevent the lower chamber from filling while the upper chamber is being emptied of its fluid. The upper chamber communicates with the exhaust pipe 7 by means of the passage 44 which is valve-controlled, as shown 65 at 47. This arrangement, it will be noticed,

prevents the exhaust from the lower chamber from effecting the compression in the upper chamber.

When it is desired to clean out the apparatus to do away with clogging, etc., all 70 that is necessary is to manipulate the three way valve 25 and compressed air will be admitted through the exhaust pipe. As the compressed air passes down through the exhaust pipe it will enter the lower chamber 75 and pass up through the oil discharge pipes. The compressed air passing up through the oil discharge pipes will, of course, unseat the check valves therein and blow out any sediment or sand which may have become 80 lodged therein and which has prevented their successful operation.

When the pump is working normally the device is so arranged that the bottoms of the oil discharge pipes 23 and 5 are always oil 85 sealed. This will prevent the air from the air intake pipes going through the oil discharge pipes and mixing with the oil and thereby destroying its value. When compressed air, however, is sent down the exhaust pipe there is nothing to prevent the compressed air from entirely emptying the chamber and passing out through the lower oil discharge 5 in the rear of the oil passing 90 therefrom into the next succeeding chamber. 95 This is done, however, only in cleaning the mechanism.

It is thought the structure and operation of the mechanism will be clear. It is to be understood, however, that the pump is 100 capable of embodiment in different forms and that the applicant does not desire to be limited to the device shown in the drawings. Wherever the term "air" occurs in the specification and claims it is to be understood 105 that the same embraces all gases which are capable of use for the purpose of forcing out a liquid in the manner described.

Having thus fully described my invention, what I claim as new and desire to secure by 110 Letters Patent, is:—

1. In a mechanism for raising fluids, a pair of superimposed elongated chambers communicating with each other and provided with heads, a compressed air passage extending through the head of the upper chamber, a passage connecting the same with the lower head, exhaust passages in said heads, valve controlled portions in each head connecting the chambers with said compressed air and exhaust passages, compressed air means within each head for actuating the valves of the heads, and means in each chamber controlled by the rise and fall of fluid therein for actuating said compressed air means. 115 120 125

2. In a mechanism for raising fluids, a pair of superimposed chambers communicating with each other and provided with heads, a compressed air passage and an exhaust 130

passage extending through the head of the upper chamber, valve controlled portions connecting the passages with said upper chamber, a compressed air conduit and an 5 exhaust conduit connecting said passages with the lower head, said lower head having valve controlled portions connecting said conduits with the lower chamber, and mechanism within each chamber controlled by the 10 rise and fall of fluid therein for controlling the valves of the respective chambers.

3. In a mechanism for raising fluids, a series of chambers communicating with each other, a compressed air conduit having portions 15 communicating with each chamber, an exhaust conduit also having portions communicating with each chamber, valves associated with each chamber for controlling the admission of compressed air thereto and the 20 exhaust, the communicating portion between each upper chamber and the exhaust conduit being provided with a check valve.

4. In a mechanism for raising fluids, a series of communicating chambers, means 25 for admitting air under pressure to each chamber, an exhaust pipe communicating with each chamber, certain of said chambers having a check valve located in said communicating portion of said exhaust pipe.

30 5. In a pump, a casing having a chamber communicating with a source of fluid supply, compressed air and exhaust conduits communicating with said chamber, a valve piston provided with valve members controlling the admission of compressed air and the exhaust, one end of said piston being reduced and located in the path of the compressed air, the opposite end of said piston being enlarged, passages connecting said 35 last-mentioned end of the piston with the source of compressed air and with the exhaust, independently mounted valves controlling said passages, and means controlled by the rise and fall of fluid within said 40 chamber for controlling said last-mentioned valves.

6. In a pump, a casing having a chamber communicating with a source of fluid supply, compressed air and exhaust conduits 50 communicating with said chamber and valve means for controlling said conduits, said valve means comprising a piston provided with valve members, one portion of the piston being larger than the other, the reduced 55 portion of the piston lying normally in the path of the compressed air, valve controlled passages connecting the other portion of said piston with the compressed air and with the exhaust, and means for controlling said last- 60 mentioned valves comprising a weight within said chamber, and a spring normally tend-

ing to raise said weight as the fluid rises therearound.

7. In a pump, a casing having a head at one end provided with a passage there- 65 through, a discharge pipe connected to one end of said passage, a check valve and cage mounted at the opposite end of said passage and a discharge pipe surrounding said cage and forming a continuation of said first- 70 mentioned pipe.

8. In a mechanism for raising fluids, a series of chambers communicating with each other, an exhaust pipe leading from one of said chambers into the next succeeding 75 chamber, said next succeeding chamber having a head, said head having an enlarged opening into which said exhaust pipe leads, an exhaust passage located in said head and communicating with said next succeeding 80 chamber and said enlarged opening, a valve located in said enlarged opening and controlling said exhaust passage, a bushing having means thereon to prevent the undue displacement of said valve, and another portion of 85 the exhaust pipe being located in said bushing.

9. In a mechanism for raising fluid, a pair of superimposed chambers communicating with each other and provided with heads, a compressed air passage extending through the head of the upper chamber, a passage connecting the same with the lower head, exhaust passages in said heads, valve-controlled portions in each head connecting the 90 chambers with said compressed air and exhaust passages, compressed air means controlled by independently movable valves within each head for actuating the first-mentioned valves, and means in each chamber 95 controlled by the rise and fall of fluid therein for actuating said last-mentioned valves.

10. In a mechanism for raising fluids, a pair of superimposed chambers communicat- 100 ing with each other and provided with heads, a compressed air passage and an exhaust passage extending through the head of the upper chamber, valve-controlled portions connecting the passages with said upper chamber, a compressed air conduit and an ex- 105 haust conduit connecting said passages with the lower head, said lower head having valve-controlled portions connecting said conduits with the lower chamber, compressed air means within each head for actuating the valves of the head, and means within each chamber controlled by the rise and fall of fluid therein for actuating said compressed air means.

110 In testimony whereof, I affix my signature. 120

ELMER A. WATTS.
